UNITED STATES PATENT OFFICE.

HERMAN T. GAY, OF BALTIMORE, MARYLAND.

SCREW-PROPELLED BOAT.

SPECIFICATION forming part of Letters Patent No. 691,258, dated January 14, 1902.

Application filed July 16, 1901. Serial No. 68,467. (No model.)

To all whom it may concern:

Be it known that I, HERMAN T. GAY, of the city of Baltimore and State of Maryland, have invented certain Improvements in Screw-Propelled Boats, of which the following is a specification.

This invention relates to certain improvements in that class of screw-propelled boats which are operated by a person seated therein, and preferably by foot-power, as will hereinafter fully appear.

In the further description of the said invention which follows reference is made to the accompanying drawings, forming a part hereof, and in which—

Figure 1 is an exterior side view of the improved screw-propelled boat. Fig. 2 is an enlarged partly-sectional side view of certain parts of the propelling apparatus, together with a portion of the bottom of the boat. Fig. 3 is a perspective view of parts of the propelling apparatus. Fig. 4 is a cross-section of certain parts shown in Fig. 2. Fig. 5 is a top view of certain parts shown in Fig. 2.

Referring now to the drawings, 1 is the boat, which may have any appropriate construction and shape. In the bottom of the boat is an opening 2, and under this opening is situated a flanged box 3. The box 3 is secured to the bottom 4 of the boat by means of a flange and bolts 5, which pass through it and the bed-plate 6 of a frame 7, hereinafter described.

9 is the screw-propeller, and 10 its shaft, which is supported at its outer end by the hanger 11. The inner end of the propeller-shaft passes through the box 3 and into a bearing 13. Water is excluded from the box 3 by means of an ordinary stuffing-box 14. On the propeller-shaft is secured the spiral gear-wheel 15, which is in mesh with the similar spiral gear-wheel 17 on a short counter-shaft 19, supported in bearing-boxes formed under the bed-plate 6. On the counter-shaft 19 is fastened a sprocket-pinion 20.

The frame 7, before referred to, consists of two uprights 22, erected on the bed-plate 6, having at their upper ends a cross connecting-piece 23.

24 is the main driving-shaft of the propelling mechanism, supported in suitable bearings forming parts of the uprights 22. This

shaft carries the driving sprocket-wheel 25, which imparts rotation to the sprocket-pinion 20 through the medium of the chain belt 29.

At the ends of the driving-shaft 24 are 55 cranks 30, the pins 31 of which are provided with rollers 32, which rest in guideways 33, formed in the vibratory bars 35, pivoted to the connecting-piece 23 of the frame 7. The cranks 30 are preferably set opposite each 60 other, and the vibratory bars have hinged pedals 37, upon which rest the feet of the operator, who sits in the seat 39.

40 is the rudder, and 41 a collapsible centerboard, which, however, is not necessary to 65 the operation of the propelling apparatus.

By clamping the bottom 4 of the boat between the bed-plate 6 and the flange of the box 3 a water-tight joint is not only effected, but the whole of the stationary portion of the 70 apparatus is rigidly tied or connected together, which prevents any motion of the frame independently of the boat-bottom and the propeller-shaft.

The operator, seated on the seat 39, places 75 his feet on the pedals 37 and by vibrating the bars 35 effects the rapid rotation of the propeller-shaft and its screw.

I claim as my invention—

A boat having an opening in its bottom, and 80 a box situated under the said opening, combined with a propeller-shaft which enters the said box and is journaled therein, a spiral gear secured to the portion of the propeller-shaft which is within the said box, a bed-plate 85 secured to the inner side of the boat-bottom and over the opening therein, a counter-shaft placed at a right angle with the propeller-shaft and having its ends journaled in bearings formed as parts of the said bed-plate, a spiral gear tight on the said counter-shaft, a sprocket-wheel tight on the said counter-shaft, a frame erected on the said bed-plate carrying a driving-shaft with a tight sprocket-wheel, a chain belt which connects 90 the two sprocket-wheels, and means to rotate the main driving-shaft and its sprocket-wheel, substantially as, and for the purpose specified.

HERMAN T. GAY.
